(57) **CLAIM**

The ornamental design for a foldable easel, as shown and described.

DESCRIPTION

FIG. 1 is a front left perspective view of a foldable easel, in folded condition.
FIG. 2 is a back view of the foldable easel of FIG. 1.
FIG. 3 is a front view of the foldable easel of FIG. 1.
FIG. 4 is a bottom view of the foldable easel of FIG. 1.
FIG. 5 is a top view of the foldable easel of FIG. 1.
FIG. 6 is a left side view of the foldable easel of FIG. 1.
FIG. 7 is a right side view of the foldable easel of FIG. 1.

FIG. 8 is a front left perspective view of the foldable easel of FIG. 1, in unfolded condition wherein left and right wings extend forward from a back portion of the foldable easel.
FIG. 9 is a left side view of the foldable easel of FIG. 8.
FIG. 10 is a front view of the foldable easel of FIG. 8.
FIG. 11 is a back view of the foldable easel of FIG. 8.
FIG. 12 is a top view of the foldable easel of FIG. 8.
FIG. 13 is a bottom view of the foldable easel of FIG. 8.
FIG. 14 is a left side view of the foldable easel of FIG. 8 pivoted clockwise on the page approximately 90 degrees from FIG. 9, for example, for resting bottom edges of the left wing, right wing, and back portion on a horizontal surface.
FIG. 15 is a front view of the foldable easel of FIG. 1 in folded condition and pivoted clockwise on the page 90 degrees from the position of FIG. 3 to place the top of the foldable easel toward the right of the page.

FIG. 16 is a front left perspective view of another embodiment of foldable easel, in folded condition.

FIG. 17 is a back view of the foldable easel of FIG. 16.
FIG. 18 is a front view of the foldable easel of FIG. 16.
FIG. 19 is a bottom view of the foldable easel of FIG. 16.
FIG. 20 is a top view of the foldable easel of FIG. 16.
FIG. 21 is a left side view of the foldable easel of FIG. 16.
FIG. 22 is a right side view of the foldable easel of FIG. 16.
FIG. 23 is a front left perspective view of the foldable easel of FIG. 16, in unfolded condition wherein left and right wings extend forward from a back portion of the foldable easel.

FIG. 24 is a left side view of the foldable easel of FIG. 23.
FIG. 25 is a right side view of the foldable easel of FIG. 23.
FIG. 26 is a front view of the foldable easel of FIG. 23.
FIG. 27 is a back view of the foldable easel of FIG. 23.
FIG. 28 is a top view of the foldable easel of FIG. 23.
FIG. 29 is a bottom view of the foldable easel of FIG. 23; and,

FIG. 30 is a left side view of the foldable easel of FIG. 23 pivoted clockwise on the page approximately 90 degrees from FIG. 24, for example, for resting bottom edges of the left and right wings on a horizontal surface.

Dashed lines in FIGS. 14 and 15 illustrate the environment of the claimed design and form no part thereof.

(Continued)

Dashed lines in FIGS. 16, 17, 18, 23, 26 and 27 are for the purpose of illustrating portions of the foldable easel that form no part of the claim.
